DESIGN FOR A FIRE EXTINGUISHER

Ignatius Nurkiewicz, Brooklyn, N. Y., assignor to
Stop-Fire Inc., a corporation of New York

Application February 19, 1948, Serial No. 144,602

Term of patent 14 years

(Cl. D16—2)

To all whom it may concern:

Be it known that I, Ignatius Nurkiewicz, a citizen of the United States, residing at Brooklyn, in the county of Kings, city and State of New York, have invented a new, original, and ornamental Design for a Fire Extinguisher, of which the following is a specification, reference being had to the accompanying drawing, forming part thereof.

In the drawing

Fig. 1 is a side elevational view of a fire extinguisher, showing my new design;

Fig. 2 is a front elevational view thereof; and

Fig. 3 is a top plan view.

I claim:

The ornamental design for a fire extinguisher, substantially as shown.

IGNATIUS NURKIEWICZ.
